[57] CLAIM

The ornamental design for set of router handles, as shown and described.

DESCRIPTION

FIG. 1 is a perspective view of a set of router handles showing my new design;

FIG. 2 is a front view of the set of router handles;

FIG. 3 is a back side view of the set of router handles;

FIG. 4 is a right side view of the set of router handles;

FIG. 5 is a left view of the set of router handles;

FIG. 6 is a top view of the set of router handles; and,

FIG. 7 is a bottom view of the set of router handles.

The broken line showing of a router in the figures above is for illustrative purposes only and forms no part of the claimed design.
